UNITED STATES PATENT OFFICE

FRANK T. SLAYTON, OF RIDLEY PARK, PENNSYLVANIA, ASSIGNOR TO JOSEPH
ROBINSON, OF NEW YORK, N. Y.

ANGLE COCK

Application filed March 14, 1930. Serial No. 435,920.

This invention relates to angle cocks used on the end of train pipes of railway cars, and among the objects is to provide an angle cock that will improve the cooperative relation between the train pipe hose of a car and the automatic connector on such car and prolong the life of the hose by minimizing the flexing of and internal stresses in the hose when the connector moves to the various positions in service.

A further object is to provide an angle cock for this purpose having an unrestricted opening therethrough formed to an easy curve whereby the minimum of impediment to the free flow of air through the valve is obtained. A further object is to provide an angle cock which may be operated from either side of the car by means of a suitable connecting rod or device. Another object is to provide improved means for anchoring the angle cock to the car body so that in case a car coupler is pulled out the minimum of damage to the train pipe will result. A still further object is to produce an angle cock for the purpose described wherein the fluid pressure carried tends to pack the valve, that is, hold it in air tight relation to its seat. Other advantages, and the detail construction of my improved angle cock, will appear from the following description and in the accompanying drawings in which.

Figure 1 is a front elevation of an automatic connector installed on a car with my improved angle cock;

Figure 2 is a side elevation of the construction shown in Figure 1;

Figure 3 is an enlarged detailed section through my improved angle cock and its associated parts, and

Figure 4 is a front elevation of the construction shown in Figure 3.

In Figure 1 of the patent to M. A. Barber, October 11th, 1927, #1,644,975, the form of angle cock now in general use on railway cars is shown. As will be noted the connector hose C of this patent is threaded into the angle cock at a considerable angle to the longitudinal direction of the train pipe itself. With such an angle cock, especially when located to the present American Railway Asso-

ciation standard for freight cars (4 3/4" rearwardly from the pulling face of the car coupler) it is practically impossible to attach a connector hose thereto without kinking the hose and setting up destructive stresses in it when the connector moves to many of the positions of service. This condition is somewhat relieved by mounting in the forward end of the angle cock an elbow curved sufficiently to bring the connector hose nipple at an angle of 90° to the longitudinal direction of the train pipe—see Figure 3 of the patent to J. Robinson March 26th, 1929, #1,706,752. But when this is done objections still exist. Among them is the objection that the hose nipple must stop at a predetermined point when threaded into the angle cock by means of an elbow nipple such as shown in the Robinson patent. To do this is often difficult and still get a tight joint. Skilled labor is required to accomplish it dependably and such labor is seldom available when hose renewals enroute are made necessary by hose bursting or failing for other cause. Then there is the old objection, inherent in the present type of angle cock, of restriction to the flow of the air through the cock—a serious objection in modern air brake operation. Continuing to remain is also the objection that the valve of the present angle cock is disposed in the vertical plane, which necessitates the opening through the valve shall be oblong instead of round unless the valve body is made objectionably large. Disposing the valve in the vertical plane also requires that the valve operating handle shall be rotated in the horizontal plane, a requirement which precludes satisfactory arrangement being made for operating the angle cock from either side of the car without a trainman having to go in between the ends of the car.

In my present invention these objections are effectively eliminated. I dispose the valve 6 in the horizontal plane, and instead of making an opening 7 through it from one side thereof I open it at the bottom and turn the opening laterally out through one side of the valve into aligned communication with the complementary opening 8 in the body 9 of the angle cock. This arrangement not

only gives a full unrestricted opening through the valve 6 but permits the valve to be packed by the pressure against the wall 10 of the fluid carried. The body 9 is provided with a tapered opening lined with a complementarily shaped lining or sleeve 11, of any suitable material, which is pressed into air tight engagement with the body by the bushing or anchor device 12. The bushing is threaded into the base 14 of the angle cock or body 9 and against the bottom of the sleeve 11 as shown. The bushing is provided with a shoulder or flange 15 which bears against a suitable bracket 16 that is rigidly anchored to the car body 17 as at 18— Figure 1. A U-shaped bolt 19 spans the bushing 12 in front of the flange 15 and passes through the forward end of the bracket 16. The body 9 is provided with a flat surface 20 at the point where it is drawn into locked engagement with the bracket 16, and this flat surface lies in the horizontal plane so that when the angle cock is clamped to the bracket the lower face 21 of the outlet or nipple 22 of the angle cock will also be disposed in the horizontal plane and at an angle of 90° to the longitudinal direction of the train pipe 23. It will be observed that the pipe 23 is threaded into the bushing 12 and that the bushing snugly embraces the pipe at 24. This arrangement rigidly anchors the angle cock and the train pipe to the car body in the correct predetermined position described, and protects them against destructive vibrations. It might appear that the bushing 12 could be readily disposed of, but if that is done and the pipe 23 threaded directly into the angle cock body 9 then the opening in the base 14 of the angle cock would be too small to receive the valve lining or bushing 11.

To hold the valve stem 6 firmly in contact with its seat in the bushing 11 when the air pressure is not turned on, I face the forward end of the angle cock body 9 as at 25 and mount thereon a suitable spring 26 of considerable resistance. This spring surrounds the lug 27 on the forward end of the valve stem 6, and is enclosed by the housing 28 of the valve stem operating handle 29, these parts being firmly locked in operative relation by a pin 30 or other suitable anchoring means. To position the valve stem 6 in its opened and closed relation to the body 9, I provide the operating handle 29 with a projection 31 which moves between stops 32 on the body. The usual freight air hose nipple 33 is threaded into the lower or outlet end 22 of the body 9 and, as aforesaid, the communication between this nipple and the front end of the train pipe 23 is a full unrestricted easy curved opening. The importance of this form of opening through an angle cock will be more fully appreciated when it is remembered that in present day long freight trains there are as many as 200 to 240 of the present

angle cocks each of which presents a substantial restriction to the movement of air through it and hence impairs the best functioning of the air brakes.

At its lower end the valve operating handle 29 is provided with an enlarged perforated head 34. This is to receive a rod or other device extending from either side of the car end inwardly into operative relation to the handle 29, whereby my improved angle cock 75 may if desired be operated from the outside of a car without the necessity of trainmen going in between the ends of the cars.

In Figures 1 and 2 my improved angle cock is shown as used with a well known type of 80 automatic connector. It may of course be used with any type of automatic connector, or wherever a valve having the characteristics of my invention is preferable to the type of valve now in use on railway cars. In Figure 1 the easy curve or flow of the train pipe 85 hose 35 of an automatic connector used in connection with my improvement, is shown, and for this service my invention has especial advantages as hereinbefore pointed out. 90

What I claim is:

An angle cock of the class described comprising in combination, a horizontally disposed body having a tapered opening therethrough, a tapered valve seat pressed into 95 said opening in air tight relation thereto, the base of said body being threaded and being provided with a flat bearing surface for positioning the body, a bushing screwed into the rear of said base into engagement with 100 said valve seat, said bushing being hollow and being threaded to receive a train pipe in air tight supporting relation thereto, the bushing being also provided with a flange of greater diameter than the diameter of the 105 threaded opening in said base, a clamp engaging said bushing in front of said flange and in retaining relation to the flange for clamping said bushing and said body rigidly to a fixed part of the car with said flat surface of the body held firmly against said fixed car part whereby said body is rigidly secured to said car part in a predetermined fixed position, said body being provided with a laterally extending hollow nipple, a tapered 110 valve stem rotatably mounted in said valve seat in the horizontal plane and having an opening leading from the base of the valve 115 forwardly and laterally into aligned communication with the opening in said nipple 120 a part of the time and into aligned communication with said train pipe all of the time, and means for resiliently holding said valve in air tight relation to said seat, said means including a projection extending forwardly 125 away from the valve, a handle anchored to said projection for rotating said valve, a spring surrounding said projection and bearing at one end against said body and at the other end against said handle, said handle 130

including a projection which moves between limiting stops on said body, said valve being so arranged that the pressure of the fluid carried acts horizontally and longitudinally against said valve stem to also force it into tight engagement with said valve seat.

In testimony whereof I hereunto affix my signature.

FRANK T. SLAYTON.
